UNITED STATES PATENT OFFICE.

THEODORE C. MENGES, OF WATERLOO, IOWA, ASSIGNOR TO ASSOCIATED MANUFACTURERS COMPANY, OF WATERLOO, IOWA.

KEROSENE-GASIFIER FOR INTERNAL-COMBUSTION ENGINES.

1,237,536.

Specification of Letters Patent. Patented Aug. 21, 1917.

Application filed August 10, 1916. Serial No. 114,128.

To all whom it may concern:

Be it known that I, THEODORE C. MENGES, a citizen of the United States of America, and a resident of Waterloo, Blackhawk county, Iowa, have invented certain new and useful Improvements in Kerosene-Gasifiers for Internal-Combustion Engines, of which the following is a specification.

My invention relates to improvements in kerosene-gasifiers for internal-combustion engines, and the object of my improvement is to furnish means adjacent to and in communication with the combustion-chamber of such an engine which may be used to employ the exhaust-gases to serve as heating-means for kerosene or heavy hydrocarbons in volatilizing them to be suitable for the ordinary consumption of the engine at all times.

This object I have accomplished by the means which are hereinafter described and claimed, and which are illustrated in the accompanying drawings, in which:

Figure 1 is an elevation of the inner face of the detachable cylinder-head which contains within its structure the internal means for gasifying the vapors of kerosene or crude oils.

Fig. 2 is an under plan view of said cylinder-head.

Fig. 3 is a transverse horizontal axial section of said cylinder-head.

Fig. 4 is a vertical transverse section of a carbureter formed and adapted to cooperate with my improved cylinder-head above illustrated.

Similar numerals of reference denote corresponding parts throughout the several views.

The cylinder-head 1 is adapted to be detachably secured over the combustion-chamber end of the cylinder of an internal combustion engine, and has ports 8 and 9 adapted to seat the valve-heads 2 and 3 respectively for admission of fuel or exhaust of the utilized gases of combustion.

Referring now to said Fig. 4, the carbureter 12, which is on a larger scale than the head 1, has openings of chambers 13 and 14 which respectively communicate with the ports 4 and 5 of said cylinder-head when the carbureter has been duly assembled with said cylinder-head. Fig. 4, which is in reversed position relative to the other figures of the drawings, shows that the chamber 13 has an air-inlet at the bottom at 23, and

contains means for introducing a supply of either gasoline or kerosene. A channel 19 serves for the introduction of a preliminary charge of gasoline to start the engine when drawn in the usual way from the chamber 13 with a mixture of air from the port 23 through the passage 10 of the cylinder-head past the valve-head 2. This conduit 19 is contracted by means of an inserted orificed plug whose orifice is controlled in delivery 65 by means of a needle-valve 20. Below the delivery-plug mentioned, another and similar delivery-plug 21 is seated in a conduit in the carbureter which is in communication with a supply of kerosene controlled by a 70 valve not shown. Kerosene vapor is drawn up through the chamber 13 and said chamber 10 by the action of the engine in forming a vacuum at the inlet-port, the vapor being also mixed with air through the port 23 in 75 a like manner. To gasify the comparatively large vapor particles of the kerosene, I employ the following means. The carbureter 12 contains a chamber 14, controlled by means of a valve 15, and which leads from 80 the port 18 of the carbureter by way of the intermediate passage 24 around and past a baffling partition 16 to the exhaust-port 5 of the cylinder-head 1. By referring to Figs. 3 and 1 it will be seen that the hollow of the 85 cylinder-head is so divided by means of internal partitions that the inlet-chamber 10 is separated in said head from the exhaust-chamber 11, the latter chamber lying side by side with said chamber 10. The exhaust-chamber 11 is divided into two diverging delivery-conduits 5 and 6, the smaller conduit 5 only being in communication with the chamber 14 of the carbureter.

The exhaust-gases are forced from the 95 conduit 5 into the said chamber 14 past its valve 15, whence the gases pass downwardly to the vent-port 18 entirely about the inner partition which separates the chamber 13 therefrom, and past the horizontal baffling-partition 16 which extends about half-way across the intermediate passage 24.

The heat of the exhaust-gases is conducted through the comparatively thin partition walls both of the carbureter and of the 105 chambered cylinder-head 1, and heats the mixed gas or vapor and air in the channels leading to the inlet-valve port 8 so highly that the particles of kerosene are broken up and reduced to a gas-like condition suitable 110

for effective combustion in the engine. My improved cylinder-head gasifying-means therefore is contrived to be effective for the purpose when in coöperation with a carbureter since the gasifying operation is kept up to the very moment when the gases pass up to the inlet-port of the engine. The gas cannot become cooled and condensed or driven back because of this construction, while the division of the exhaust-gases provides a better clearance for them.

Having described my invention, what I claim as new, and desire to secure by Letters Patent, is:

15 1. A gasifier for an internal-combustion engine, consisting of a detachable hollow head for the cylinder, said head having separated chambers in communication with the combustion-chamber of the engine by means 20 of valve-controlled ports, one of the cham-

bers being adapted to receive the exhaust-gases of the engine, and said head having means for dividing the voided gases into two streams divergently, of which one stream is caused to pass over the wall separating said chamber from the other or inlet-chamber of the head.

2. In an internal-combustion engine, a head having an exhaust-chamber in communication with the combustion-chamber of the engine by means of a valve-controlled port, said chamber being formed into divergent conduits, and said head having exit-ports for said conduits.

Signed at Waterloo, Iowa, this 4th day of 35 Aug. 1916.

THEODORE C. MENGES.
